(57) CLAIM

The ornamental design for a ceiling fan, as shown and described.

DESCRIPTION

FIG. 1 is a top perspective view of a ceiling fan according to a first embodiment of the invention;

FIG. 2 is a bottom perspective view of the ceiling fan of FIG. 1;

FIG. 3 is a top view of the ceiling fan of FIG. 1;

FIG. 4 is a bottom view of the ceiling fan of FIG. 1;

FIG. 5 is a front side view of the ceiling fan of FIG. 1, with rear, right, and left side views being mirror images thereof; FIG. 6 is a top perspective view of a ceiling fan according to a second embodiment of the invention;

FIG. 7 is a bottom perspective view of the ceiling fan of FIG. 6;

FIG. 8 is a top view of the ceiling fan of FIG. 6;

FIG. 9 is a bottom view of the ceiling fan of FIG. 6;

FIG. 10 is a front side view of the ceiling fan of FIG. 6;

FIG. 11 is a right side view of the ceiling fan of FIG. 6;

FIG. 12 is a rear side view of the ceiling fan of FIG. 6; and,

FIG. 13 is a left side view of the ceiling fan of FIG. 6.
